UNITED STATES PATENT OFFICE.

EDWARD SCHWALBACH, JR., OF BROOKLYN, NEW YORK, ASSIGNOR TO A. G. JENNINGS, OF SAME PLACE.

DESIGN FOR EMBROIDERY FOR MITTS, &c.

SPECIFICATION forming part of Design No. 19,166, dated June 18, 1889.

Application filed May 16, 1889. Serial No. 311,074. Term of patent 7 years.

To all whom it may concern:

Be it known that I, EDWARD SCHWALBACH, Jr., of Brooklyn, Kings county, New York, have invented and produced a new and original Design for Embroidery for Mitts, Gloves, &c., of which the following is a specification, reference being had to the accompanying drawing, forming part thereof, which is a face view of a portion of a mitt having my newly- designed embroidery on it.

The leading feature of my design consists of a substantially W-shaped embroidery figure for the backs of mitts, gloves, &c.

In the accompanying drawing, the letter B represents a portion of a mitt, and A represents my newly - designed embroidery for mitts, gloves, &c., which is a substantially W-shaped figure.

I claim—

The design for embroidery for mitts, gloves, &c., herein shown and described.

EDWARD SCHWALBACH, JR.
